UNITED STATES PATENT OFFICE.

JOHN E. MOLLE, OF STURGEON BAY, WISCONSIN.

TYPE-WRITING MACHINE.

No. 813,570.

Specification of Letters Patent.

Patented Feb. 27, 1906.

Application filed December 28, 1904. Serial No. 238,575.

To all whom it may concern.

Be it known that I, JOHN E. MOLLE, a citizen of the United States, residing at Sturgeon Bay, in the county of Door and State of Wisconsin, have invented a new and useful Type-Writing Machine, of which the following is a specification.

This invention relates to type-writing machines, and is designed to obtain in a simple and effective manner a prompt and positive response of the type-bars to the operation of the keys and to effect cushioning of the key-action, so as to prevent breaking of any of the parts thereof should the action become jammed in any manner and at the same time to cushion the depression of the keys, and thereby prevent the sudden jar upon the fingers of the operator, as is usual with ordinary forms of type-writing machines when the type strikes the platen.

A further object of the invention is to simplify the connection between the key-stems or plungers and the type-bars and to permit of the ready application and replacement of such connections without interfering with any of the other parts of the machine.

A still further object of the invention is to have the key-action mounted so as to be put in and taken out as a whole from the main frame, thereby to facilitate the repairing of this portion of the machine.

Another object of the invention is to provide for preventing accidental disconnection of the key-action from the type-bars and at the same time to permit of the convenient disconnection of these parts whenever desired.

A still further object of the invention is to provide an improved construction of type-bar which operates to prevent pounding of the type against another type-bar should several keys be simultaneously struck and a corresponding number of type-bars thrown up against the platen, thereby to prevent injury to the type.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a longitudinal sectional view taken through the lower portion of the frame of the type-writing machine having the improvements of the present invention. Fig. 2 is an inverted plan view thereof. Fig. 3 is a detail sectional view on the line 3-3 of Fig. 1. Fig. 4 is a detail perspective view of the yieldable rock-bar forming the connection between one of the keys and the corresponding type-bar. Fig. 5 is a detail view of the latch connection between the rock-bar and the heel of the type-bar. Fig. 6 is a detail perspective view of one of the type-bars. Fig. 7 is a detail cross-sectional view of the type-bar support. Fig. 8 is a detail view of one of the keys and its stem or plunger.

Like characters of reference designate corresponding parts in each and every figure of the drawings.

In illustrating the present embodiment of this invention there has been shown the base portion 1 of the frame of the machine, which is in the form of a substantially horizontal open rectangular frame-support upon the usual feet 2. At the back of the frame there is a bowed or segmental type-bar support 3, which has its concaved face uppermost and supported at each end by a standard 4. The front edge of this type-bar support is provided with a series of substantially upright notches or seats 5, and in the under side of this notched portion of the support is a longitudinal groove 6, extending from end to end of the support. Each type-bar 7 has its heel portion received in one of the seats or notches 5 and provided with a perforation 8 in alignment with the groove 6 of the type-bar support, through which passes a fulerum-rod 9, which is seated in the groove and is removably supported therein by means of a headed fastening 10, (best shown in Fig. 7,) one of such fastenings being at each end of the type-bar support and preferably in the nature of a screw having its head underlying the rod 9, so as to detachably support the same in place.

An arcuate rest-bar 11 is carried by the type-bar support 3 and is projected in front thereof and beneath the type-bars, so as to support the latter in their normal inactive positions. This rest-bar is provided with a casing or covering 12, of rubber or other suitable material, to cushion the type-bars when returning to their normal positions. The free end of each type-bar is provided with a

head 13, which is offset at the rear side of the bar in substantial parallelism therewith, with the type 14 carried upon the rear side of the offset head and located outwardly beyond the extremity of the type-bar. By this construction of type-bar should a plurality of type-bars be simultaneously thrown up against the platen 15, which has been indicated by dotted lines in Fig. 1 of the drawings, the shoulder 16 of one of the bars will strike the front side of the free extremity of the type-bar which is in rear thereof, and thereby prevent its type from striking against said other type-bar, and thus preventing injury to the type.

The keys 17 of the present invention are arranged in banks in the usual manner and are provided with pendent stems or plungers 18, working through perforations in a stepped series of guide-bars 19, carried by and extending across the open top of the front portion of the main frame 1. As best indicated in Fig. 8, it will be noted that the lower end of each key-stem is provided with a crank-bend 20, and the extremity of the crank-bend is provided with a transverse projection or pin 21, for a purpose as will be hereinafter described.

Within the main frame 1 is a key-action frame, including front and rear bars 22 and 23 and opposite side bars 24, which produce a substantially rectangular open frame, the rear frame-bar 23 being disposed in advance of the rear ends of the sides 24 and provided throughout its upper edge with a rearwardly-directed flange 25. The rear extremity of the sides of the key-action frame are supported upon suitable projections or shoulders 26, extending inwardly from the adjacent sides of the main frame 1, there being setscrews 27, piercing the rear extremities of the sides 24, for frictional engagement with the inner faces of the adjacent sides of the main frame. Adjacent the front end of each side of the main frame 1 there is a threaded perforation 28, in which fits an adjustable setscrew 29, having a conical inner end to enter a smooth perforation 30 in the adjacent side 24 of the key-action frame. By this means the key-action frame is removably supported within the main frame of the machine and may be readily removed therefrom by releasing the screws 27 and 29, whereupon the front end of the frame may be tilted up and drawn out through the front of the main frame. It will here be noted that the standard 4, which carries the type-bar support 3, is connected to the key-action frame, as indicated at 31, and therefore the type-bar support and type-bars are removable with the key-action frame.

The connection between each key-stem and the corresponding type-bar includes a substantially horizontal flat rock-bar 32, formed of spring metal and capable of being

twisted, each end of the bar being bent at substantially right angles thereto to form crank-terminals 33 and 34, which are pierced at their outer ends by perforations 35 and 36. This rock-bar is supported upon a cylindrical rod 37, which loosely pierces the crank-arms adjacent the upper side of the rock-bar and projects beyond the ends of the latter, with its rear end removably fitted in a perforation in the rear end bar 23 of the key-action frame 7 and its front end carried by the front end 22 of said frame. By preference a plate 38 is secured to the inner face of the front end bar 22 of the key-action frame, so as to project above and below said bar, and is provided with perforations arranged in vertical sets of three, as best indicated in Fig. 3 of the drawings, for the reception of the front ends of the several rods 37.

It will here be explained that the rods 37 and rock-bars 32 are arranged in sets of three, one above the other, and, as best shown in Fig. 1 of the drawings, the rods 37 extend from the front to the back of the key-action frame, while the rock-bars 32 are somewhat shorter, with the front end of the lowermost bar in advance of the front end of the next adjacent upper bar, so as to accommodate the front cranks 33 to the corresponding key-stems, each of which has its crank-pin 21 engaged with the perforation 35 of the adjacent crank 33, so that a depression of the key operates to lock the bar 32 upon its supporting-rod 37. The rear ends of the rock-bars successively project beyond the next adjacent lower bar in order that there may be no interference between the connections from the several rear cranks to the respective type-bars. To prevent undue endwise play of each rock-bar 32 upon its supporting-rod 37, there are provided holding devices in the nature of elastic sleeves 39, preferably helical springs, which snugly embrace the rod 37 at the opposite ends of the rock-bar 32 with a frictional grip sufficient to prevent endwise play of the rock-bar upon the rod, while at the same time these holding-sleeves may be forcibly shifted upon the rod to permit of the bar 32 being adjusted endwise upon the rod for engaging and disengaging the crank 33 with one of the key-stems. Another elastic sleeve 40 is provided upon the front portion of the rod 37, so as to bear against the rear side of the front of the key-action frame, while the rear sleeve 39' fits snugly between the rear end of the rock-bar 32 and the rear end of the frame, whereby the rod 37 is held against endwise play through the perforations in the front and rear ends of the key-action frame. The rod 37 can of course be forcibly moved in an endwise direction from the frame when it is necessary to make repairs.

For connecting the rear end of each rock-bar with its corresponding type-bar there is

a link 41, which is provided at its lower end with a hook 42, detachably engaged with the perforation 36 in the adjacent crank-arm 34, the upper end of the link having a hook or lateral projection 43, engaged with a perforation 44 in the offset rearwardly-projected heel portion 45 of the type-bar. At intermediate points the link 41 is provided with a pair of eyes 46 and 47, through which passes a latch-bar 48, that is supported by a helical spring 49, embracing the bar, with its lower end resting upon the eye 47 and its upper end bearing against a shoulder or projection 50 upon the intermediate portion of the latch-bar, whereby the latter is yieldably supported in an elevated position with its upper end lapping the heel of the type-bar and engaging the catch projection 43, thereby to prevent lateral displacement of the link 41 from the type-bar. By manually depressing the latch the catch projection 43 may be disengaged from the type-bar whenever desired. A helical spring 51 has its lower end hooked about the lower end portion of the latch-bar 48 beneath the guide 47, with its upper end connected to the type-bar support 3, preferably by being hooked into a perforation in the rear projected perforate edge of a flange or plate 52, carried by the under side of the type-bar support and projected in rear thereof, whereby the type-bar is yieldably maintained in its normal depressed position and the adjacent crank 34 of the rock-bar is held at its upper limit, with the corresponding key 17 also at its upper limit.

By reference to Figs. 1 and 3 of the drawings it will be noted that there is a substantially horizontal guard-bar 53 extending transversely across the front portion of the key-action frame in rear and adjacent each key-stem, there being one such bar for each bank of keys and the several bars being arranged in vertical stepped relation, with their corresponding ends carried by a stepped support 54, which is secured to the adjacent side 24 of the key-action frame. As clearly indicated in Fig. 1 of the drawings, each key-stem works between one of the guard-bars 53 and the crank 33 of the adjacent rock-bar 32, whereby displacement of the crank-pin 21 from the crank 33 is prevented.

In manipulating the machine when a key is depressed in the usual manner its stem operating through the adjacent crank 33 rocks the bar 32 upon its support 37, thereby swinging the rear crank-arm 34 downwardly and pulling down upon the link 41, which draws down the heel of the adjacent type-bar and throws the free end of the latter upward into engagement with the platen. It will here be noted that the connection between each key and its corresponding type-bar is very simple and includes comparatively few joints, whereby lost motion is reduced to the minimum.

65 By reason of the fact that the rock-bar 32 is

of spring material and capable of being elastically twisted when the type-bar is arrested by contact with the platen the rock-bar will be slightly twisted under the continued depression of the key, and in view of the elastic nature of the rock-bar the key-action will be cushioned so as to prevent jamming and breaking of any of the parts thereof, and the usual sudden jar upon the fingers of the operator is entirely overcome in a very simple and efficient manner without the employment of extraneous springs or other cushioning devices. Upon release of the key the spring 51 operates to automatically return the key and the type-bar to their normal inactive positions, as hereinbefore described, and the torsionally bent rock-bar 32 will also resume its normal condition preparatory to another operation.

It will here be explained that the rock-bar 32 is of course slightly shortened when torsionally twisted, and the members 38 and 39 are designed to operate as holders or stops for contact with the ends of the bar when it resumes its normal position, thereby to prevent the bar from creeping endwise upon its supporting-rod, as such endwise creeping would twist and jam the connections between the rock-bar, the key-stem, and the link 41.

From the foregoing description it will be understood that with the exception of the stepped guide members 19 all the parts of the present invention are carried by the key-action frame and may therefore be fitted and removed from the main frame of the machine as a whole, which materially facilitates the assembling and also repairing of the several parts of the present invention. By removing the guard-bars 53 the crank-pins 21 of the key-stems may be disengaged from the front crank-arms of the rock-bars 32, and when the links 41 have been disengaged from the rear ends of the rock-bars the supporting-rods 37 and the rock-bars may be conveniently removed from the frame, whereby repairs may be readily made and the several parts of the device again assembled in a very simple and expeditious manner.

Having fully described the invention, what is claimed is—

1. The combination with a type-bar and a key, of a connecting-rod terminating at opposite ends in cranks which are respectively connected to the key and the type-bar, and a support engaging the crank-arms intermediate of their ends with the arms rotatable thereon, the connecting-bar being free to rotate upon the support for actuating the type-bar by a depression of the key and said connecting-bar also capable of being torsionally twisted when the type-bar strikes the platen to permit further depression of the key and thus cushion the action.

2. The combination with a type-bar and a

key, of a torsionally-twistable rock-bar terminating at opposite ends in cranks which are respectively connected to the type-bar and the key, and a supporting-rod loosely 5 piercing the crank-arms.

3. The combination with a type-bar and a key, of an elastic torsionally-twistable rock-bar terminating at opposite ends in cranks which are respectively connected with the 10 type-bar and the key, a supporting-rod loosely piercing the cranks, and means carried by the rod to prevent creeping of the rock-bar under its torsional elastic action.

4. The combination with a type-bar and a key, of a torsionally-twistable elastic rock-bar terminating at opposite ends in cranks which are respectively connected with the type-bar and the key, a supporting-rod loosely 15 piercing the cranks, and elastic 20 sleeves frictionally embracing the rod and in engagement with the opposite ends of the bar to prevent creeping of the latter under its torsional action.

5. The combination with a type-bar and a key, of a rock-bar provided with opposite cranks which are respectively connected to the type-bar and the key, and a supporting-rod loosely 25 piercing the cranks.

6. In a key-action for type-writing machines, the combination of a rock-bar having a crank provided with a perforation, a guard member adjacent the crank, and a key having a stem provided with a lateral pin detachably engaging the perforation in the 30 crank and working between the latter and the guard member to prevent displacement of the stem.

7. A type-writing machine having a main frame, projections extending inwardly from the frame at one end thereof, a key-action 40 frame removably supported at one end upon the projections, set-screws carried by the key-action frame adjacent the projections for frictional engagement with the main frame, and other set-screws piercing the 45 other end of the main frame for detachable engagement with the key-action frame.

8. In a type-writing machine, the combination with a frame, of a type-bar support, 50 type-bars mounted upon the support, a key-

action frame having its opposite ends provided with corresponding perforations, rods having their ends supported in the perforations of the key-action frame, rock-bars mounted upon the rods and connected to the corresponding type-bars, and keys connected to the rock-bars for rocking the same upon their supporting-rods.

9. In a type-writing machine, the combination of a frame, a type-bar support carried by the frame above the rear end thereof, type-bars mounted upon the support, rods extending between the front and back of the frame, rock-bars mounted upon the rods and terminating at opposite ends in cranks, connections between the rear cranks and the type-bars, guard-bars carried by the front of the frame and extending thereacross adjacent the front cranks, and keys having stems connected with the respective front cranks 70 and working between the latter and the adjacent guard-bars.

10. In a type-writing machine, the combination with a frame, a type-bar support, a type-bar mounted thereon, a rod having its ends supported in openings in opposite ends of the frame, a torsionally-twistable elastic rock-bar having terminal cranks pierced by the rod, an operative connection between one of the cranks and the type-bar, a key connected to the other crank, an elastic sleeve frictionally embracing the rod and bearing against one end of the rock-bar and the adjacent end of the frame, another elastic sleeve frictionally embracing the rod and bearing against the opposite end of the rock-bar, and a third elastic sleeve embracing the rod and bearing against the other end of the frame, said sleeves operating to prevent creeping of the rock-bar upon the rod and prevent accidental endwise displacement of the rod through the openings in the frame.

In testimony that I claim the foregoing as my own I have hereto affixed my signature in the presence of two witnesses.

JOHN E. MOLLE.
